CLAIM

The ornamental design for a body warmer, as shown and described.

DESCRIPTION

FIG. 1 is a front view of a body warmer showing our new design;

FIG. 2 is a rear view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof; and,

FIG. 8 is another rear view of the embodiment of FIG. 1, shown with a different broken line disclosure.

The broken lines in the drawings are intended to show environmental structure and form no part of the claimed design.
